UNITED STATES PATENT OFFICE.

WERNER O. OLSON, OF EAST ORANGE, NEW JERSEY, ASSIGNOR TO ASHER MANUFACTURING COMPANY, OF IRVINGTON, NEW JERSEY, A CORPORATION OF NEW JERSEY.

SUPPLY DOOR FOR WASH WHEELS.

Application filed April 28, 1925. Serial No. 26,535.

This invention relates to supply doors for wash wheels, or washing machines, of the type comprising a pair of co-axial horizontal cylinders of which the outer cylinder is 5 stationary and the inner one is movable in relation thereto and adapted to contain the articles being washed.

It is a general object of the present invention to provide a novel and improved supply door for wash wheels.

More particularly it is an object of the present invention to provide a supply door for wash wheels which is self-washing on its inner face and which prevents the deposition of washing material upon the lower edge of the main door opening.

Another object of the present invention consists in the provision of a supply door or shutter adapted to close an opening in the main door of the outer drum of a wash wheel, said shutter having a hinged connection with the door, which hinged connection is contained within the space enclosed by the outer drum.

Still another object of the present invention consists in the provision of a device adapted to be mounted upon the main door of the wash wheel and to support by a hinged connection a supply door, said device also serving as a stop to limit the movement of the main door in closing direction and to re-enforce the edge of the main door adjacent the supply door opening.

Other and further objects of the invention will become more apparent to those skilled in the art by reference to the accompanying drawing and following specification, wherein is disclosed a single exemplary structure, with the understanding, however, that various changes and modifications may be made therein, such as in the size, shape, proportions, arrangement, and material of the various parts without departing from the spirit of the invention or the scope of the appended claims.

In said drawing:

Figure 1 is a partial elevation of a wash wheel, showing one of the main filling doors and its associated supply door,

Figure 2 is a partial transverse vertical section through a wash wheel taken on line 2-2 of Figure 1, and

Figure 3 is a partial, horizontal section

through the supply door taken on line 3-3 of Figure 2.

In my copending application, Serial No. 17,748, filed March 23, 1925, I have disclosed a supply door for wash wheels which is adapted to close an opening in the main or charging door of the outer drum or cylinder. This supply door is of the self-washing type and is adapted to cooperate with a handle bar, used for opening and closing the main door, in order to retain the supply door in its open position. In this earlier application, the supply door was pivoted, intermediate its circumferential height, by pivots outside of the main door. In the present form, however, the supply door is hinged to the main door at the lower edge of the supply door and this hinged connection is arranged a material distance inside of the main door, in fact, such a distance that the hinge is radially closer to the axis of the drum than is the inner surface of the drum.

This construction permits substantially the entire supply door to be within the outer circumference of the drum and within the main door, so that it is more readily subjected to spray from the revolving inner drum. Thus any of the washing materials clinging to its surface will be washed off before it is necessary to again use the supply door for the purpose of inserting other materials which might be neutralized by the action of any of the earlier material sticking to the door. By having the lower edge of the supply door projecting over and inwardly of the bottom edge of the main door opening, leakage between the main door and the drum is prevented, and the lodgment of material on this edge is obviated.

In the drawing, wherein is illustrated a well-known type of wash wheel, 10 represents the stationary outer drum or cylinder, usually formed of wooden staves, as shown, and provided with bands or hoops 11 to retain the staves together. Suitable supporting means such as feet 12 serve to maintain the drum in a horizontal position. The inner cylinder or drum 13 is mounted for rotation or oscillation in any desirable manner, not shown, and is composed of any suitable material perforated to allow for the flow of the washing fluid. The drums are spaced apart a suitable distance, and access

is gained to the inner drum, wherein the material to be washed is placed, by means of an opening, not shown, passing through it, which opening is closed by any satisfactory 5 type of door, not shown. A corresponding opening 14 is provided in the outer drum 10 so that when the two openings are lined up, access may be had to the interior of the inner drum. This opening 14 is adapted to 10 be covered by a main or large door 15, which is usually made of sheet metal and slides circumferentially over the surface of the drum between the guides 16 and 17 under the bands 11. The opening 14 is usually 15 above the horizontal center of the outer drum, and the edges of the opening are preferably reenforced by metal strips such as 18, which may be secured in any desired manner to the shroud which protects the outer 20 surface of the drum.

The main door 15 is provided with a rectangular supply opening such as 20 through which may be introduced such materials as soap, washing powder, bluing, etc., without 25 the necessity of opening the larger door or stopping the rotation of the inner drum. This opening is preferably of considerable length and may be almost as long as the main door, but its circumferential width or 30 height is relatively small in order that the hand of the operator may not be introduced therethrough and possibly be injured.

The main door being formed of sheet metal, the material thereof is weakened by 35 the provision of the opening 20, and therefore the upper edge of the door is re-enforced by a longitudinal bar or strip 21 of suitable material securely fastened thereto by riveting or otherwise. The lower edge of 40 the opening 20 is re-enforced by the angle bar 22 having the flange 23 which is riveted or welded to the inner surface of the main door and the flange 24 which projects inwardly so as to overhang the inner edge 45 of the re-enforcing strip 18, as shown in Figure 2. This angle bar 22 not only reinforces the main door, but provides a stop for it, limiting its downward movement by the engagement of the flanges 23 and 24 50 with the re-enforcing strip 18. The flange 24 also serves to support one of the wings of the hinge 26, which is preferably of the type commonly known as a piano hinge. This hinge supports the lower edge of the 55 supply door or shutter 27 which is adapted to close the opening 20 to prevent splashing out of the liquid contained in the drum 15. This door or shutter is formed of sheet metal, as shown, and reaches from the hinge 26 circumferentially around the drum, so 60 that its upper edge 27' engages the outer surface of the main door just under the re-enforcing bar 21 where it may be held by any suitable form of catch such as 28.

65 In the open position, shown by dotted lines

in Figure 2, the shutter 27 rests upon the top surface of the flange 24 of the angle bar 22, as shown in dotted lines, and its upper edge 27' rests against the handle bar 28 which is provided with the rabbet 29 to receive it. 70 This handle bar serves not only as a stop to limit the outward movement of the supply door, but as a handle for the manipulation of the main door, and for this purpose it is made with its under side of channel 75 form to increase its rigidity.

The handle bar is supported from a pair of sector-shaped side plates 30 formed integral with the bases 31, which are rigidly secured by riveting or any other suitable 80 manner to the outer surface of the main door adjacent the edges of the supply opening, and serve not only as supports for the handle bar, but as re-enforcements for the sides of the supply opening. These sector-shaped 85 side plates extend within the opening a sufficient distance so as to close the space between the edges of the door 27 and the opening 20, so that there can be no leakage of liquid around the door. Each of the sector-shaped side plates 30 is provided with an inwardly projecting flange 32 upon which the door rests when open, thus forming a lap joint so that the door together with the side 90 plates forms in effect a hopper having lap joints at its corners through which washing material can be poured into the drum. A suitable knob or handle 33 may be provided on the door 27 to facilitate its operation. 100

The above construction provides a supply door in which the lower edge projects over the inside edge of the door opening at 25, so as to prevent supplies from being spilled on this lower edge and also causing any 105 spray which strikes the inside of the supply door, and serves to wash it, to drain back into the interior of the drum rather than leak out at the lower edge of the main door, which it would do if this protection were 110 not provided. The supply door, when closed, has a tight fit along its upper edge with the outer surface of the main door, and its ends fit snugly between the side plates 30 at all times, thus effecting a substantially 115 water-tight closure. When open, a convenient supply hopper is provided closed on three sides and having the fourth side opening into the drum. The handle bar 120 cooperates with the upper edge of the supply door to limit its outward movement, and by this support prevents any possibility of bending the supply door so that it would not form a tight closure, thus enabling it to be made of a thinner material and effecting a reduction in its cost. 125

Having thus described the invention, what is claimed as new and desired to be secured by Letters Patent is:

1. In a wash wheel, in combination, a 130

- drum having an opening therein, a main door slidable to close said opening and having a supply opening therein, a shutter for said supply opening, and means pivoting 5 said shutter to said door within the space enclosed by the inner walls of said drum.
2. In a wash wheel, in combination, an outer horizontal cylinder having an opening above the horizontal center thereof, a main 10 door slidable circumferentially over said cylinder to close said opening and having a supply opening therein, a shutter fitting through said opening at an angle to the plane thereof and hinged to said main door, said hinge 15 connection extending inwardly beyond the plane of the inner surface of said cylinder.
3. In a wash wheel, in combination, a relatively thick, horizontal, outer drum having an opening above the horizontal center thereof, a relatively thin main door slidable circumferentially on the outside of said drum to close said opening and having a supply opening therein, a supply door adapted to close said opening, a reinforcing strip 20 secured to the inner face of the main door, and extending in beyond the plane of the inner wall of said cylinder, and a hinge joining the inner edge of said strip and the supply door.
4. In a wash wheel, in combination, a relatively thick, horizontal, outer drum having an opening above the horizontal center thereof, a relatively thin main door slidable circumferentially on the outside of said 25 drum to close said opening and having a supply opening therein, a supply door adapted to close said opening, a stop member on the inside of the lower edge of said main door to engage the lower edge of the opening and means pivoting said supply 30 door to said stop member.
5. In a wash wheel, in combination, a relatively thick, horizontal, outer drum having an opening above the horizontal center thereof, a relatively thin main door slidable circumferentially on the outside of said drum to close said opening and having a supply opening therein, a supply door adapted to close said opening, a stop member projecting 35 inwardly from the lower edge of the supply opening and serving to engage with and cover the lower edge of the main door opening, and a hinge joining the inner edge of said stop to the lower edge of said supply 40 door.
6. In a wash wheel, in combination, a horizontal drum having an opening therein, a door slidable circumferentially to cover said opening and having a supply opening 45 therein, a handle bar extending transversely of said door, a reinforcing member inside the lower edge of said door and a shutter 50 adapted to close said supply opening, said shutter passing through said opening, and a hinge joining said shutter to said reinforcing member, said handle bar forming a stop to limit the opening of said shutter.
7. In a wash wheel, in combination, a horizontal drum having an opening therein, a door slidable circumferentially to close 55 said opening and having near its lower edge a supply opening, a reinforcing strip inside the lower edge of said supply opening and adapted to overhang the edge of the main opening, side plates secured to the edge of 60 said supply opening and normal to the surface of said door, a handle bar joining said plates above the surface of said door and a shutter hinged at its lower edge to said reinforcing strip, fitting between said side 65 plates and resting on said handle bar when open to thus form a supply hopper.
8. In a wash wheel, in combination, a horizontal outer cylinder having a filling 70 opening therein, a main door slidable circumferentially to close said opening and having a supply opening therein, an angle bar extending the length of said supply 75 opening, one flange of said bar being secured to the inner side of said main door below said supply opening, the other flange projecting inwardly and over the lower edge of said filling opening, and a shutter having its lower edge pivoted to the inwardly projecting flange of said reinforcing bar and 80 adapted to close said opening.
9. In a wash wheel, in combination, a horizontal outer cylinder having a filling 85 opening therein, a main door slidable circumferentially to close said opening and having a supply opening therein, an angle bar extending the length of said supply 90 opening, one flange of said bar being secured to the inner side of said main door below said supply opening, the other flange projecting inwardly and over the lower edge of 95 said filling opening, vertical sectors at the ends of said supply opening abutting the ends of said shutter, and flanges on said sectors receiving said shutter when open.
10. In a wash wheel, in combination, an outer horizontal cylinder having an opening 100 above the horizontal center thereof, a main door slidable circumferentially over said cylinder to close said opening and having a supply opening therein, a shutter fitting through said opening and hinged to said main door, said hinged connection being inside of the inner wall of the cylinder, said 105 shutter having its upper edge overlapping the outside of the main door when closed.

In testimony whereof I hereunto affix my signature.

WERNER O. OLSON.
